CLAIM

The ornamental design for a wallet, as shown and described.

DESCRIPTION

FIG. 1 is a front perspective view of a wallet;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines showing cards inserted into the wallet are for the purpose of illustrating environmental structure and forms no part of the claimed design.

1 Claim, 4 Drawing Sheets
